UNITED STATES PATENT OFFICE

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY

PACKING

Application filed March 17, 1925. Serial No. 16,095.

The present invention relates to packings generally as for reciprocating rods with particular reference to fluid pressure tools such as pneumatic sand rammers.

In order that a pneumatic sand rammer may operate efficiently it is essential that the packing for the rammer rod maintain a tight seal for the outer end of the piston chamber since motive fluid is admitted thereto at the end of each forward movement of the piston to effect its return stroke. The usual practice has been to have the packing glands make a loose fit in the forward end of the cylinder with the packing compressed therebetween and with the cylinder bore serving as a wall for the packing. Not only is this loose fitting not conducive to a tight sealing of the piston chamber but it also leaves the piston free to exert a force against the packing at every forward stroke which tends to destroy the packing.

Among the objects of the invention are to avoid relative movement of the packing members which results in the destruction of the seal and of the packing material, to reduce the amount of packing material required with a reduction in the pressure necessary to maintain the seal, to provide for manual adjustment of the packing without the use of tools, to facilitate the handling and inserting of new packings, to provide a new form of molded packing and protective container therefor, and in general to improve prior structure in the interests of more efficient and satisfactory service.

In order to illustrate the invention and the manner of its use one concrete embodiment thereof is shown in the accompanying drawings in which:

Fig. 1 is a longitudinal sectional view through the forward end of the cylinder of a pneumatic sand rammer;

Fig. 2 is a right end elevation of the part shown in Fig. 1;

Fig. 3 is a view similar to Fig. 1 on a reduced scale showing the manner of inserting a new packing, and

Fig. 4 is a perspective view of the molded packing in its container.

The embodiment of the invention chosen

for the purpose of illustration is shown in the drawings as sealing the forward end of the piston chamber of a pneumatic sand rammer comprising the cylinder or barrel 5 in which piston 6 reciprocates, the latter having attached thereto or integral therewith a stem 6a which projects beyond the cylinder 5 and carries the butt or pein (not shown). The motive fluid admitted to the front end of the piston chamber through passage 7 to drive piston 6 on its back stroke is sealed against escape through the forward open end of the cylinder by the following construction. A packing gland member 8 in the form of a hollow cylinder or sleeve is rigidly secured within the open end of the cylinder as shown. One method of rigidly securing member 8 in the cylinder is to provide the latter with internal screw threads 5a and the member with external screw threads 8a. Opposite slots as 8b permit the use of a spanner wrench for inserting member 8a and a shoulder 8c cooperating with a similar shoulder within cylinder 5 serves as a stop. The cylinder bore 9 of member 8 receives stem 6a with a sliding fit and serves as a bearing for the latter. Member 8 is provided with a counter bore 9a in which packing material 10 is seated surrounding stem 6a and a second gland member 11 in the form of a cylinder sleeved over stem 6a makes a close sliding fit with counterbore 9a and telescopes within member 8 to place packing 10 under compression. Member 11 is of substantial length as indicated and projects beyond cylinder 5. A gland nut 12 having a head 12a with a bore 12b loosely receiving stem 6a is provided with a cylindrical extension 12c arranged loosely to telescope over the projecting portion of member 11 and is exteriorly threaded for engagement with the interior threads 5a of cylinder 5. Head 12a is formed with a rim extending beyond cylinder portion 12c and interposed between this rim and the end of the cylinder 5 and surrounding projection 12c is a coiled spring 13 whose ends 13a and 13b are removably seated in sockets 5b and 12d respectively in cylinder 5 and nut head 12a to hold the manually adjustable nut 12 in adjusted position.

Fig. 4 illustrates the manner in which packing material 10 is arranged for insertion in the above recited gland. As indicated the material is molded to the proper size and shape and enclosed in a cylindrical holder, container or envelope 14 of any suitable material, such as cardboard. The manner of inserting the packing is clearly indicated in Fig. 3. With gland member 8 in position as shown the molded packing 10 in its container as a unit is sleeved over the piston stem 6a until the container 14 abuts the outer end of member 8. Gland member 11 is then sleeved over the stem 6a and is telescoped within the container 14 forcing the molded packing 10 into the counterbore 9a of gland member 8, the member 11 being forced through packing 10 and into telescopic engagement with member 8 until the parts reach the position shown in Fig. 1, the packing then being seated in its recess. The container or envelope 14 is now removed from the stem 6a and the gland nut 12 with its locking spring is applied and set up to put packing 10 under the desired compression. The tool is then ready for use.

From the above it will be apparent that the rigid securing of gland member 8 within the cylinder end prevents relative movement of the parts and provides a good bearing for the stem 6a, that the packing material is contained wholly within the gland member 8 and protected from wear through relative movement of the adjacent parts, that the other gland member 11 telescoping within member 8 and closely fitting the same provides additional bearing surface for stem 6a and closely confines the packing material within rigid walls, that by this gland construction only a small amount of packing material and a relative low pressure of the same are required to seal the cylinder, that the telescoping engagement of member 11 and gland nut 12 serve as an additional support for the latter, that the low pressure required on packing 10 permits manual adjustment of nut 12, and that the locking spring 13 retains the nut 12 in its adjusted position.

While but one embodiment of the invention has been herein shown and described it is to be understood that the invention is not limited to the specific details thereof but covers all changes, modifications and adaptations within the scope of the appended claim. The packing herein disclosed is claimed per se and as to the method of applying the same in my copending application, Serial No. 95,842, filed March 19th, 1926, as a division of this application.

I claim as my invention:

In a fluid pressure tool having a cylinder with an open end and a piston reciprocable in the cylinder with a stem projecting therefrom, the cylinder having a long counterbore threaded substantially throughout its length

and forming an internal shoulder, packing means for said piston stem comprising an elongate gland member sleeved over said stem and threaded into said counterbore to provide a rigid bearing for said stem, said member having a shoulder to engage the internal shoulder of said cylinder, packing material surrounding said stem within said member, a second gland member sleeved over said stem and telescoping within said first member with a sliding fit, said second member being of substantial length and projecting well beyond said cylinder, a nut sleeved over said stem and having a cylindrical extension telescoping over the projecting portion of said second gland member, said extension being exteriorly threaded to screw into said counterbore of said cylinder in spaced relation to said first gland member, said gland members and nut cooperating to permit tightening of said packing material by the operator of the tool by grasping the nut with his hand and turning it.

Signed by me at Detroit, Michigan, this 12th day of March, 1925.

EDWARD W. STEVENS.
